4 Sheets-Sheet 4

UNITED STATES PATENT OFFICE.

FRANK JOHN BAXTER, OF CHICAGO, ILLINOIS.

SHEET-SEPARATING MACHINE.

Application filed October 1, 1927. Serial No. 223,317.

This invention relates to machines for counting sheet material, particularly sheets of papers.

As is well known to persons familiar with the printing and binding of various kinds of pamphlets, magazines, catalogues and the like—which may be designated generally as books—such books, for the most part, consist of paper of substantially the same quality, all printed in ink of the same color. At the present time, many such books contain other pages, usually of a much better grade of paper and bearing cuts, illustrations and printed matter executed in colors. In accordance with what, so far as I know, is universal present practice, such pages are printed separately from the main portion of the book and are inserted therein in proper position by hand and are commonly known as inserts. In accordance with common practice, also, a considerable number of said inserts are printed on a single large sheet, which is later cut to form single inserts of proper size. In printing large editions of books, as, for example, magazines which have a large circulation, catalogues of large mail order houses, and the like, large quantities of the different inserts are, of course, required, necessitating a large run of sheets of such inserts, said sheets being run separately and a count being kept of the number of sheets run.

Due to the large wastage which occurs in the printing and handling of said inserts and, to an extent, to inaccuracies in counting, which is usually done by hand, by weight, or by measure, it frequently happens that discrepancies occur between the number of sheets of inserts billed and the number which are finally actually available for use, frequently resulting in controversies and disagreements between the printer and publisher or between the printing and the binding departments of large printing establishments, which take contracts for furnishing the books complete. Almost inevitably, also, such discrepancies result in large loss to the printer and binder, due to holding the presses and binding equipment, and idleness of the workman.

Obviously, it is much more economical and, therefore, much preferable, that the full number of inserts desired be printed at a single run, as to prepare the presses for a short run to make up a shortage will be relatively very expensive as compared with running

the full number desired at a continuous operation.

The object of my invention is, therefore, to provide a counting and registering machine by which the exact number of sheets of inserts furnished on a given order will be accurately counted, thus obviating all possibility of variance between the number billed and the number actually furnished.

Another object of the invention is to provide a machine for counting sheets of paper which will be simple, strong and durable in construction and accurate and dependable in operation.

To effect the objects of the invention, my improved counting machine comprises the various features, combinations of features and details of construction hereinafter described and claimed.

In the accompanying drawings, in which my invention is fully illustrated,

Figure 1 is a top plan view of a sheet counting machine embodying my invention and improvements;

Figure 2 is a side elevation of the machine viewed from the lower side of Fig. 1;

Figures 2^a and 2^b are enlarged, fragmentary, detail sectional views;

Figure 3 is an enlarged plan view, partly in section, on the line 3—3 of Fig. 1, parts of the machine being omitted; and

Figures 4 and 5 are side elevations, substantially similar to Fig. 2, with operative parts of the machine other than the sheet separating means proper omitted, respectively showing said separating means at substantially opposite limits of their movement.

Describing my improved sheet counting machine with particular reference to the drawings, A designates the frame of the machine as a whole, upon which the operative parts of said machine are mounted. A desirable form of frame shown consists of spaced upright standards 1, formed at the lower ends of which are feet 2, adapted to rest upon a suitable supporting surface as a bench or table indicated at a. The upper ends of said standards are connected by a transverse member 4 made in the form of an angle, one flange of which is disposed horizontally and the other substantially vertically with what may be designated its front face substantially flush with the corresponding edges of the standards 1. Said standards 1 may conveniently and will preferably be

made of suitable cast metal, preferably cast iron. The machine frame also comprises a plate 5, the front end of which is secured to the top side of the horizontally disposed flange of the angle 4 and which projects rearwardly therefrom, said plate being skeletonized or cut away in the rear of the angle 4, as shown at 6, so that said plate will not interfere with contemplated movement of certain actuated parts of the machine, the rear portion of said plate thus forming two spaced sections 7 and 8 secured to which, adjacent to their rear ends, are upright standards 9 and 10. Formed on the standards 9 and 10 adjacent to their upper ends, are frontwardly projecting arms 11 and 12 formed at the outer ends of which, respectively, are bearing bosses 13 and 14. Specifically, the construction of the frame of the machine may be varied within a wide range, as my invention contemplates the use of any desired or approved form of frame suitable for the purpose.

The operative parts of the machine are driven from a shaft 15 rotatably mounted in bearings formed in bosses 16 and 17 formed at the upper ends of the standards 9 and 10.

Speaking generally, said operative parts comprise means for supporting a pack of sheets of paper to be counted designated at B; means for supporting one corner of the sheets forming said pack in turned up position as shown at b; means for subjecting the turned up corners of said pack to intermittent pressure to prevent the sheets from becoming jammed together; suction means for separately withdrawing the turned up corners of the lowermost sheet of the pack from engagement with the means for supporting it in turned up position and depositing it in flatwise position upon the support for said pack; and counting means associated with said sheet separating means.

A very important feature of my improved counting machine resides in the fact that my improved machine is constructed and arranged for counting the sheets of the pack from the bottom up, thus providing for placing additional sheets in the machine on top of those already contained therein, thus providing for continuous operation of the machine without stopping, until required amount for one load or platform, which would be impossible if the blanks were counted from the top downwardly, thus necessitating that, when a pack in the machine is counted, it be removed and replaced by another pack, during which time the machine will be shut down and idle.

As shown, the pack of sheets B is supported upon a table, indicated by the reference character C, which may exemplify any usual or approved form of receding table, of which several different kinds are old and well known in the printing industry and which

readily can be furnished by mechanics familiar with the art without a description thereof in detail.

The pack of sheets B rests upon the table C and is confined thereon in operative position with reference to the separating and counting means, by a suitable stationary frame, designated as a whole D, the sides of which converge symmetrically towards the longitudinal center of the machine proper at an angle of ninety degrees, that is, the angle formed by the edges of a pack of sheets.

The frame D comprises side members 19 and 20 and an intermediate section 21 which extends at an angle of substantially 135 degrees to the side members 19 and 20, respectively, and which is riveted, spot-welded or otherwise rigidly secured to the upright flange of the transverse angle-shaped section 4 connecting the side standards A of the machine frame. Secured to and depending from the side members 19 and 20 of the stationary frame B are side boards or plates 22 which are adapted to embrace the lateral edges of the pack B when in operative position on the table C.

As shown, the means for supporting the corners of the sheets to be counted in turned up position, shown at b, comprises, first what may be designated a combing wheel 23 secured to rotate with a shaft 24 rotatably mounted in bearings in bosses 25 formed on brackets 26 secured to and which depend from the side members 19 and 20 of the stationary frame D. Said brackets will preferably be cast and may be secured to the members 19 and 20 of the frame D by rivets or other suitable means.

Rotation is adapted to be imparted to the shaft 24 from the main driving shaft 15 of the machine by a belt 27 indicated by dotted lines adjusted to grooved pulleys 28 and 29 secured to the shafts 15 and 24, respectively.

The turned up corners b of the pack of sheets B rest in contact with the combing wheel 23 which, due to the fact that the corners of the sheets of the pack engage said combing wheel at different distances from their corners, respectively, preferably is substantially spool-shaped, comprising conical end sections 30 and 31 and an intermediate substantially cylindrical and relatively small section 32, thus permitting the corners of the sheets having the shortest engagement with the perimeter of said spool to enter between the ends of said spool so as to engage the central portion thereof, while the sheets having longer engagement with said spool will engage the same at progressively greater distances from the longitudinal center thereof.

In addition to the combing wheel 23, the means for supporting the pack of sheet B also comprises stationary stops adapted to contact with the lowermost sheet of the pack B. Each of said stops comprises a head portion

33 which contacts directly with the paper, and a shank 34, which has screw threaded engagement with holes formed adjacent to the lower ends of lugs 35 secured to and which depend from the side members 19 and 20 of the stationary frame B, thus providing for adjusting the position of said stops. Said stops are positioned somewhat below the combing spool 23.

10 Also, to prevent the turned up corners b of the pack of sheets B from folding over and becoming jammed into the space below the stationary stops formed by the heads 33, means are provided below said stationary stops for intermittently subjecting the turned up corners of the pack of sheets to a pushing action which will prevent them from jamming into the space below the stationary stops.

The stationary stops 33 are in duplicate at opposite sides of the combing wheel 23 and are positioned in such relation to the supporting table C and the combing wheel 23 that when, in the operation of the machine, a sheet is withdrawn from engagement with the combing wheel 23—means for which purpose will presently be described—the corner of said sheet will also be withdrawn from engagement with said stops 33, thus permitting it to fall flatwise onto the table C or a pack of blanks supported thereon.

It is owing to the described position of said stops 33 that it is possible to make them stationary, as, if the separating means did not withdraw them from engagement with said stops 33 they would not be free to fall flatwise upon the table, in the manner contemplated and the machine would be inoperative.

In the preferable construction shown, also, the means for supporting the sheets of the pack B in turned up position also comprises stops which engage the lowermost sheet of the pack B below and somewhat outside of the stationary jaws formed by the heads 33 and in such relation that the separating means will not withdraw the sheets from engagement therewith. Thus, in order that the separated sheets may fall into flatwise position on the table C it is obviously necessary, that whenever a sheet is withdrawn, said stops be retracted a sufficient distance from the pack so as to clear the corners of the sheets as they fall into flatwise position on the table C.

As shown, said stop, which I will describe in the singular, is designated as a whole E, and each thereof comprises a bar 36 fitted to reciprocate endwise on a bearing surface formed on a foot 2 of a frame standard 1, being secured in position and guided in its movement by a headed stud 37 which extends through a slot 38 formed lengthwise in the bar 36 and the lower end of which has screw-threaded engagement with a hole formed in the feet 2 of said side standard A. To provide for adjusting the operative position of said reciprocating stop, the stop proper is formed by a screw stud 39 threaded to a hole formed lengthwise through the end of the bar 36, formed on which is a rounded head 40 adapted to bear directly against the pack of blanks. The stud 39 is adapted to be secured in different adjusted positions by means of a lock nut 41, in a usual manner.

In the operation of the machine, longitudinal reciprocating movement is adapted to be imparted to the bar 36 and thus to the head 40 carried thereby, by means as follows: Secured to a shaft 42 rotatably mounted in the bearing bosses at the ends of the arms 11 and 12 of the standards 9 and 10 are depending lever arms 43, the lower ends of which are connected by a cross rod 44 secured thereto in any suitable manner as by screws 45 which extend through holes formed in the lower ends of said levers and which have screw-threaded engagement with holes formed in the ends of the rod 44. Said levers 43 are operatively connected with the rear end of the reciprocating bars 36—that is the ends thereof remote from the pack of sheets—by means of link members 46 and 47, the remote ends of which are pivotally connected to the levers 43 and to the bars 36, respectively, and the adjacent ends of which are pivotally connected to each other, the connection of the link member 47 to the bar 36 and of the link members 46 and 47 to each other being constructed and arranged to permit flexure of each of said joints in one plane only and the planes of flexure of the joints connecting said link members to each other and the link member 47 to the bars 36 being positioned in different planes, the axes of said joints being preferably positioned substantially at right angles to each other.

With the described construction, it is obvious that the bars 36 will have great freedom of movement to conform to variations of alignment of the lines of connection between the levers 43 and said bars 36.

Pivotal movement is adapted to be imparted to the levers 43 to impart endwise movement to the bars 36 to advance the stops 40 into contact with the lowermost sheet of the pack B by a cam 48 secured to the main shaft 15 of the machine, co-operating with which is a roller stud 49 mounted on a lever arm 50 secured to rotate with the shaft 42 to which the levers 43 are secured; and pivotal movement is adapted to be imparted to the levers 43 to retract the stops 40 from engagement with the pack of sheets B by springs 51 which connect said levers 43 with a fixed part of the machine frame. Retraction of said lever arms by said springs is controlled and limited by the operating face 52 of the cam 48 other than the portion thereof by which the stops 40 are advanced, which limits retraction of the levers 43.

Beginning with the lowermost sheet of the pack of sheets B the turned up corners of said

sheets are adapted to be withdrawn successively one at a time from engagement with the combing wheel 23 and the stationary stops 33 and released so that they will fall flatwise 5 onto the table C or on the top of a pack of sheets lying thereon, by means of suction nozzles 53 which communicates with a chamber 54 formed in a header 55. Said header 55 is secured to the outer end of a pipe 56, 10 with the chamber 54 in said header in open communication with the bore of said pipe, the end of said pipe 56 remote from the header 55 being rigidly secured to a head 57, the end of said pipe, as shown, having screw- 15 threaded engagement with a hole formed in said suction head.

The head 57 is pivotally mounted on a stud 58 secured in a boss 59 formed at the lower end of a lever 60 pivoted adjacent to its upper 20 end to a stud 61 secured in the frame standard 10. The lever 60 extends above the stud 61 and rotatably mounted on said extension is a roller stud 62 which runs in contact with a cam 63 secured to the main driving shaft 15 25 of the machine.

The means for supporting the oscillating head 57 also comprises a rearwardly extending arm 64 formed thereon which is connected by a rod 65 with one end of a lever 66 pivoted 30 between its ends to the stud 61 and mounted on said lever at the opposite side of the pivot from the point of attachment thereto of the rod 65 is a roller stud 67 which runs in contact with a cam 68 secured to the main driving shaft 15.

The lever 60 and thus the head 57 pivoted to the lower end thereof is adapted to be maintained normally retracted by a spring 69 which connects said lever with a fixed part 40 of the machine, as shown, with a stud 70 secured to the frame standard 10. Also, the end of the lever 66 to which the rod 65 is connected is maintained normally depressed by a spring 71 which connects the arm of said 45 lever to which said rod 65 is connected with a rigid part of the machine, as shown, with the stud 70.

With the described construction, it is obvious that, as the shaft 15 rotates, the conjoint 50 action of the cam 63 and spring 69 will cooperate to impart oscillating movement to the lever 60 to advance the head 57 and thus the suction nozzles 53 into contact with the turned up corner of the lowermost sheet of the pack 55 of sheets B and to retract said suction nozzles, while the conjoint action of the cam 68 and the spring 71 will operate to impart oscillatory movement to the head 57 upon its supporting stud 58 secured to the lower end 60 of said lever 60, the relation being such that when the suction nozzles 53 are advanced into contact with the pack of sheets B, said suction nozzles will also be in their extreme raised 65 position so that they will just clear the underside of the combing wheel 23 as they ad-

vance, and the relation being such also that substantially simultaneously with the beginning of the rearward movement of the suction nozzles, under the influence by the spring 69, said nozzles will be quickly depressed substantially to the position shown in Fig. 4, 70 thus effecting disengagement of the turned up corner of the lowermost sheet of the pack B from the combing wheel 23 and the stationary stops 33.

The relation is such also, that simultaneously with the initial retraction of the suction nozzles 53, the bars 36 carrying the stop studs 40, will be quickly retracted so as to permit a sheet withdrawn and released by 80 said suction nozzles to fall flat upon the table C, and such also that said stop will be quickly advanced into contact with the turned up corners b of the pack B as soon as the withdrawn sheet has been released and has assumed a flat position on the table C.

To provide for adjusting the position of extreme elevation of the suction nozzles 53, the rod 65 is preferably made in separate sections connected by a turn-buckle 72. Obviously, by turning the turned buckle 72 to increase or decrease the operative length of the rod 65, the arm 64 on the head 57 will be raised or depressed, thus correspondingly depressing or raising the suction nozzles 53. 95

Suction is adapted to be applied to the suction nozzles 53 at intervals by suitable connection between said nozzles and a suction pump, notshown. As shown, said connection comprises a pipe 73 secured in a hole or opening 74 formed in the outer end of the stud 58 by means of a quarter turn fitting 75 and a nipple 76, in a usual manner, said tube being adapted to be connected with the suction pump by means of a flexible tube, not shown, 100 connected to the outer end of said pipe.

The hole or opening 74 in the stud 58 extends beyond the inner end of the nipple 76 and formed in the wall of the stud is a hole or opening 77, see particularly Fig. 2^a, communication of which with a hole 78 formed in the head 57 and which is in open communication with the bore of the tube 56, is adapted to be made and cut off by oscillation of the head 57 on the stud 58, in the operation of 115 the machine, thus intermittently producing suction at the suction nozzles 53.

Also a groove 79 is formed circumferentially in the outer surface of the stud 58 adapted intermittently to connect the opening 78 in the head 57 and thus the bore of the tube 56, with a hole or opening 80 formed in the head 57 and which connects the bearing for the stud 58 with atmosphere, the relation being such that when the hole or passageway 77 is in communication with the hole 78, communication of the groove 79 with said openings 78 will be cut off, and vice versa.

The relation is such also that the hole or opening 77 will be in communication with the 130

hole or opening 78 when the head 57 is in its pivotal position corresponding to engagement of the suction nozzles 53 with the turned up corner of the lowermost sheet of the pack 5 B, thus producing suction at said suction nozzles and causing the sheet of paper with which said suction nozzle is in contact to adhere thereto, and the relation being such also that shortly after the sheet engaged by the 10 suction nozzle is disengaged from the combing wheel 23 and the stationary stops 33, said passageway 77 will pass out of communication with the hole or opening 78 and the groove 79 will be brought into communication therewith thus permitting air to enter the tube 56 and suction nozzles 53, breaking the suction at said nozzles and releasing the paper therefrom, so that it will be free to fall flatwise on the table C or a pile of sheets 15 resting thereon.

Mounted in association with my improved machine is a counter indicated at F which, in use, will be operatively connected with a movable part of the machine, whereby said 20 counter will register the number of sheets counted by the machine.

I claim:

1. In a machine of the type specified, the combination of means for supporting a pack 30 of sheets comprising means for supporting one corner only of said pack in turned up position, and means for withdrawing said turned up corners of said sheets from engagement with the supporting means therefor one 35 at a time and in succession, beginning with the lowermost sheet of the pack.

2. A machine as specified in claim 1, in which the means for supporting the corner of the pack in turned up position comprises a 40 combing wheel, and means for rotating the same.

3. A machine as specified in claim 1, in which the means for supporting the corner of the pack in turned up position comprises a 45 combing wheel, means for rotating the same, and stationary stops below said combing wheel.

4. A machine as specified in claim 1, in which the means for supporting the corner of the pack in turned up position comprises a 50 combing wheel, means for rotating the same, and stationary stops below said combing wheel, said stationary stops being adjustable.

5. A machine as specified in claim 1, in 55 which the means for supporting the corner of the pack in turned up position comprises a combing wheel, means for rotating the same and movably supported stops below said combing wheel, and means for advancing said stops into contact with the turned up corners of the pack of sheets and to retract said stops to permit a withdrawn sheet to pass the same.

6. A machine as specified in claim 1, in 60 which the means for supporting the corner

of the pack in turned up position comprises a combing wheel, means for rotating the same and movably supported stops below said combing wheel, and means for advancing said stops into contact with the turned up 70 corners of the pack of sheets and for retracting said stops to permit a withdrawn sheet to pass the same comprising pivoted arms, the lower ends of which are connected to said movable stops, and means for imparting oscillating movement to said arms.

7. A machine as specified in claim 1, in which the means for supporting the corner of the pack in turned up position comprises a combing wheel, means for rotating the same, and movably supported stops below said 80 combing wheel, and means for advancing said stops into contact with the turned up corners of the pack of sheets and for retracting said stops to permit a withdrawn sheet to pass the same comprising a rock shaft, arms secured thereto, the lower ends of which are connected to said movable stops, and means for imparting oscillating movement to said 85 rock shaft.

8. A machine as specified in claim 1, in which the means for supporting the corner of the pack in turned up position comprises a combing wheel, means for rotating the same, and movably supported stops below 90 said combing wheel, and means for advancing said stops into contact with the turned up corners of the pack of sheets and for retracting said stops to permit a withdrawn sheet to pass the same comprising a rock shaft, arms secured thereto, the lower ends of which are connected to said movable stops, and means for imparting oscillating movement to said rock shaft comprising a driven 95 shaft, a cam secured thereto, an arm secured to said rock shaft, and a projection thereon which runs in contact with said cam.

9. A machine as specified in claim 1, in which the means for supporting the corner of the pack in turned up position comprises a 100 combing wheel, means for rotating the same, and movably supported stops below said combing wheel, and means for advancing said stops into contact with the turned up corners of the pack of sheets and for retracting said 105 stops to permit a withdrawn sheet to pass the same comprising a rock shaft, arms secured thereto, the lower ends of which are connected to said movable stops, and means for imparting oscillating movement to said rock shaft, comprising a spring or springs applied to said arms, and means to turn said rock shaft against the force of said spring or springs comprising a driven shaft, a cam secured thereto, an arm secured to said rock 110 shaft, and a projection thereon which runs in contact with said cam.

10. A machine as specified in claim 1, in which the means for withdrawing sheets 115 from engagement with the supporting means

therefor comprises suction nozzles adapted to be connected with suction means, means for supporting said suction nozzles constructed and arranged for advancing said nozzles into contact with the pack and for retracting the same, and means for depressing said nozzles abruptly at the beginning of their retraction.

11. A machine as specified in claim 1, in which the means for withdrawing sheets from engagement with the supporting means therefor comprises suction nozzles adapted to be connected with suction means, means for supporting said suction nozzles constructed and arranged for advancing said nozzles into contact with the pack and for retracting the same, and means for depressing said nozzles abruptly at the beginning of their retraction, said nozzle supporting means comprising a pivoted lever, a head pivoted thereto, a pipe secured in said head, a header secured to the front end of said pipe in which said suction nozzles are secured, and which is provided with a chamber which communicates with said nozzles and supporting pipe, and means for imparting oscillating movement to said lever.

12. A machine as specified in claim 1, in which the means for withdrawing sheets from engagement with the supporting means therefor comprises suction nozzles adapted to be connected with suction means, means for supporting said suction nozzles constructed and arranged for advancing said nozzles into contact with the pack and for retracting the same, and means for depressing said nozzles abruptly at the beginning of their retraction, said nozzle supporting means comprising a pivoted lever, a head pivoted thereto, a pipe secured in said head, a header secured to the front end of said pipe in which said suction nozzles are secured, and which is provided with a chamber which communicates with said nozzles and supporting pipe, and means for imparting oscillating movement to said lever comprising a spring applied to said lever for imparting movement thereto in one direction, and a driven shaft, a cam secured thereto and a projection on said lever which rides on said cam for turning said lever pivotally against the force of the spring applied thereto.

13. A machine as specified in claim 1, in

which the means for withdrawing sheets from engagement with the supporting means therefor comprises suction nozzles adapted to be connected with suction means, means for supporting said suction nozzles comprising a pivoted lever, a head pivoted thereto, a pipe secured in said head, a header secured to the front end of said pipe in which said suction nozzles are secured, means for imparting oscillating movement to said lever, and means for imparting oscillating movement to the head pivoted to said lever upon its pivotal axis comprising a rearward projection on said lever, a pivoted lever, a rod which connects said lever with the projection on said head, a driven shaft, a cam thereon, a projection on said pivoted lever which engages said cam, and a spring applied to said lever in opposition to said cam.

14. A machine as specified in claim 1, in which the means for withdrawing sheets from engagement with the supporting means therefor comprises suction nozzles adapted to be connected with suction means, means for supporting said suction nozzles constructed and arranged for advancing said nozzles into contact with the pack and for retracting the same, and means for depressing said nozzles abruptly at the beginning of their retraction, and means for making and breaking the suction at said suction nozzles.

15. A machine as specified in claim 1, in which the means for withdrawing sheets from engagement with the supporting means therefor comprises suction nozzles adapted to be connected with suction means, means for supporting said suction nozzles constructed and arranged for advancing said nozzles into contact with the pack and for retracting the same, and means for depressing said nozzles abruptly at the beginning of their retraction, and means for making and breaking the suction at said suction nozzles controlled by movement in operation of the means for supporting and actuating said suction nozzles.

16. A machine as specified in claim 1, in which the combing wheel is spool-shaped.

In witness that I claim the foregoing as my invention I affix my signature this 23 day of September, A. D. 1927.

FRANK JOHN BAXTER.
